STORE-COUNTER.

1,035,223.

Specification of Letters Patent. Patented Aug. 13, 1912.

Application filed October 7, 1910. Serial No. 585,883.

To all whom it may concern:

Be it known that we, JOHN S. MITCHELL and SERENUS M. COLBURN, of Minneapolis, Hennepin county, Minnesota, have invented 5 certain new and useful Improvements in Store-Counters, of which the following is a specification.

Store counters are usually built up, having a top, and front and end panels or walls 10 securely fastened together and braced on the floor in a suitable manner. It is almost impossible to move a counter so constructed without racking or twisting it out of shape and frequently the top or the panels are 15 broken in the moving operation. Furthermore, the front panel is located close to the outer edge of the top and prevents a person from sitting close to the counter and 20 compels the placing of the stools or chairs for the customers out a considerable distance into the aisle.

The object, therefore, of our present invention is to provide a knock-down counter 25 capable of being easily separated and moved from place to place, and having a top of suitable thickness so that it will be self sustaining, suitable standards being provided at intervals to support the top the desired 30 distance from the floor.

30 A further object is to provide a counter having an open space beneath the outer portion of the top which will allow the customer to sit close to the counter, or will permit the stools or chairs to be set in under 35 or close to the counter when they are not in use, and in case the stools are fastened to the floor they may be located almost directly under the edge of the counter top.

The invention consists generally in a 40 counter consisting of a comparatively thick top with end and middle columns therefor, and a partition or panel located centrally with respect to the top of the counter and extending lengthwise thereof.

45 Further the invention consists in various constructions and combinations, all as hereinafter described and particularly pointed out in the claims.

In the accompanying drawings forming 50 part of this specification, Figure 1 is a front elevation of a store counter embodying our invention, Fig. 2 is a plan view of the same, Fig. 3 is an end view, Fig. 4 is a sectional view on the line $x-x$ of Fig. 1.

55 In the drawing, 2 represents the counter

top, built up, preferably, of strips of wood and substantially four inches in thickness, although the thickness may be varied according to the size of the counter.

3 represents the columns for the table 60 consisting, preferably, of suitable castings, such as bronze, ornamented in any desired way, and having flanges 4 through which screws pass into the bottom of the counter top. These columns are arranged, preferably, as shown in Fig. 3, three at each end of the counter and two in the middle thereof. Two of the columns at each end are preferably in substantially the same plane, extending transversely of the counter, while 70 the third column is located near the middle of the counter at right angles substantially to the other columns. All of the columns are preferably flattened in form and their bases have broad bearing surfaces to rest 75 upon the floor while the capitals of the columns are of substantially the same size as the bases and have broad, flat tops to which the counter bed or top is secured, as above described. These columns form very sub- 80 stantial supports for the counter and their bases have such broad bearing surfaces on the floor and they are so stable in construction that a securing means for the bases will be unnecessary.

85 Between the end and middle columns we provide an upright panel 5 extending from the floor to the bottom of the counter top beneath the middle portion and secured by suitable means, such as the brace 6. This 90 panel does not support any portion of the counter but merely fills the openings between the end and middle columns and provides a place on one side, or back of the counter, where boxes and wrapping paper 95 may be piled without being in view of the customer. On the other side of the panel a similar space is formed between the top supports to allow room for the customer to sit close to the counter, and also allow 100 the stools or chairs to be pushed up close or in under the counter when not in use, assuming, of course, that the stools or chairs are not fastened to the floor. In case the stools are secured to the floor they may be 105 set almost directly under the edge of the counter, or much nearer than usual with counters constructed in the ordinary way.

The counters are made in sections of suitable length placed end to end, and any de- 110

sired number of the counters may be used, according to the space required to fill. In shipping, the counters are taken apart and packed in knock-down form and in moving

5 from place to place in a store the top may be taken off and the columns set up separately wherever it may be desired to locate the counter.

10 The ornamentation of the shafts of the columns may, of course, be varied according to the taste of the designer and in various ways the details of construction may be modified without departing from our invention.

15 We claim as our invention—

1. A store counter comprising upright columns having bases provided with flat bearing surfaces adapted to rest upon the floor and capitals also having flat surfaces, 20 a counter bed removably supported on the flat surfaces of said capitals, there being three columns at each end of said bed, two of said columns being disposed transversely of said bed, one on each side of the longitudinal center line thereof, the third end column being disposed at right angles substantially to the plane of the other two end columns and abutting against the inner portions of the same, and a vertical partition or 25 30 panel extending lengthwise of the counter beneath and near the longitudinal middle line thereof and having a suitable bracing

means, the inner faces of said transverse end columns being seated against the end portions of said panel, substantially as described. 35

2. A store counter comprising upright columns having bases provided with flat bearing surfaces adapted to rest upon the floor, the capitals of said columns also having flat bearing surfaces, a bed adapted to rest upon said capitals, there being a column on each side of the longitudinal center line of said counter at each end thereof and transversely with respect to said counter, a 40 panel extending lengthwise of said counter beneath the longitudinal middle portion thereof and against which panel the end columns are seated, a middle column disposed beneath the transverse middle portion 45 of said bed on one side of said panel and seated against the same, unobstructed spaces being provided beneath said bed between said middle column and the end columns on the same side of said panel, and a space being also provided beneath said bed on the opposite side of said panel. 50 55

In witness whereof, we have hereunto set our hands this 29th day of September 1910.

JOHN S. MITCHELL.
SERENUS M. COLBURN.
